GRATE FOR UNDERFEED STOKERS

Gordon M. Peltz, Portland, Oreg., assignor to
Iron Fireman Manufacturing Company, Port-
land, Oreg.

Application April 3, 1937, Serial No. 134,786

4 Claims. (Cl. 126—146)

This invention relates generally to underfeed stokers, and particularly to a grate therefor.

The main object of this invention is to construct a form of pin hole grate for underfeed stokers by means of which air will be so delivered to the fuel bed as to make it accessible to every portion of the fuel bed in the shortest possible time.

The second object is to accomplish this result without requiring any machining of the parts, that is to say, to employ only a casting process in the construction of the grate.

The third object is to construct a conical grate which will be self-centering.

These, and other objects, will become more apparent from the specification following as illustrated in the accompanying drawing, in which:

Fig. 1 is a fragmentary vertical section through the conical grate and the retort section of a stoker.

Fig. 2 is a fragmentary elevation showing portions of three of the grate sections with the intermediate section cross-hatched for the sake of clearness.

Fig. 3 is a fragmentary perspective showing the manner in which the grate sections engage each other.

Fig. 4 is a horizontal section taken along the line 4—4 in Fig. 1.

Similar numbers of references refer to similar parts throughout the several views.

Referring in detail to the drawing, there is shown a retort base 10 within which is contained the retort 11 which communicates by means of a coal tube 12 with a coal supply section not shown. A worm 13 conveys fuel through the tube 12 into the retort 11. The retort 11 has a circular opening 14 in the center of the top 15 of the base 10.

Mounted on the top 15 is a grate casing 16 whose under side 17 is provided with spokes 18 which terminate in the lowermost grate section 19 which is concentric with the opening 14. Bolts 20 secure the grate casing 16 to the base 10. Air enters the retort base 10 through the opening 10A and escapes therefrom through the opening 10B into the space 10C.

The position of the toothed wheel 21 which carries a clinker breaking bar (not shown) is indicated. The wheel 21 is revolvable on the cylindrical portion 22 of the casing 16. It is desirable to provide the under side 17 of the casing 16 with an annular tongue 23 which extends into a sealing groove 24 to the top 15. The upper portion 25 of the casing 16 is flanged outwardly

and provided with a sealing groove 26 and bolt holes 27.

Referring more particularly to the grate sections, it will be seen that the lowermost section 19 has formed on its top side the sloping slots 28. These slots 28 have between them the raised lands 29 which are approximately one-third as wide as the slots 28. The lands 29 are of uniform width and are equally spaced.

Superimposed above the section 19 are the 10 various grate sections 30, each of which has formed on its upper side the slots 28 and the lands 29. Each section 30 has also formed on its under side the radial slots 28L and lands 29L. In Figs. 2, 3 and 4 are clearly shown the manner 15 in which the raised lands or lugs 29 and 29L occupy their respective slots 28L and 28. The shape of the parts is such as to readily permit their reproduction by casting same in sand.

It will be noted in Fig. 3 that the inner end 31 of each downturned land 29L is made approximately vertical in order to eliminate the necessity of casting sharp points. The same is true of the outermost end 32 of each upturned land 28. It will be observed that the faces 33 and 34 of the slots 28 and 28L and the lands 29 and 29L slope downwardly toward the vertical axis of the retort. Naturally, this slope decreases toward the uppermost section 30 where it is substantially horizontal due to the outward flaring 30 of the fire pot. It will be noted that when the parts are thus superimposed, there is formed a plurality of air spaces 35 on each side of each land 29 and 29L, each of which has a smaller area than would be obtainable if the slots were 35 cast directly in the parts.

By this method air is delivered to the combustion in a great many small streams without the necessity of employing parts which are difficult to make and more difficult to maintain when made.

It will be noted in Fig. 4 that the raised lands or lugs 36 are somewhat wider than are the lugs 29. The opposite faces 37 of each pair of lands 36 are so spaced as to engage the opposite faces 37L of the corresponding slots 28L. It is desirable to provide at least three pairs of lugs 36 in order to insure the proper centering of each grate section 30. This also prevents the relative rotation of the sections 30. This is important 40 since if the sections 30 were permitted to rotate with relation to each other, they would cause a variation in the sizes of the air spaces 35.

Above the uppermost grate section 30 is placed an outwardly turned fire pot rim 38 which is 55

held down by a ring 39 by means of the bolts 40 which extend through the portion 25 of the casting 16.

It may be seen from the foregoing that by this construction it is possible to deliver to the fire a quantity of air which will be available to every portion of the fuel bed due to the fact that the air is delivered through a great number of small openings or air spaces 35, and in spite of the fact that the lugs 29 and 29L of one part fit very loosely into the slots 28 and 28L of the next adjacent part, the spaces 35 are held uniform by the lugs 36 which prevent the relative rotation of adjacent grate sections 30. The lugs 36 also insure the vertical alignment of the parts by centering them about the vertical axis of the retort.

It is immaterial how a section 30 is placed upon the next section below as long as they are approximately in vertical alignment since the downwardly extending lugs of one section will fit properly between the upwardly extending lugs of the next lower section regardless of the relative positions to which these parts are rotated.

While I have illustrated these sections as having the thickened lugs 36 on the top side, it will be understood that they could also be placed on the bottom side without departing from the spirit of the invention.

Throughout the specification I have referred to the slots and lands as being radial and I have so illustrated them. These could, of course, depart from radial lines without detracting from the usefulness of the device.

I am, of course, aware that numerous forms of sectional grates have been constructed in the past. It is, therefore, not my invention to cover such devices broadly but I do intend to cover all such forms and modifications thereof which fall fairly within the appended claims.

40 I claim:

1. A plurality of superimposed outwardly flaring grate rings, the upper and lower sides of which are provided with substantially radial slots having raised lands between same, the lands of one ring being capable of registering with the slots of an adjacent ring, the slots having a considerably greater width than do said lands, the purpose of which is to permit each land to divide its related slot into two small slots and means for preventing the relative rotation of the respective grate ring elements. 5

2. A pair of superimposed outwardly flaring grate rings, the top of the lower ring and the bottom of the upper ring having wide radial slots formed therein between which are relatively narrow lands, said lands including a plurality of pairs of lugs whose adjacent sides are spaced to engage the opposite faces of a pair of lands forming a part of the adjacent grate ring. 15

3. A pin hole grate consisting of a plurality of superimposed circular sections, the engaging faces of which have wide radial slots formed therein forming relatively narrow lands therebetween, the lands of one section being adapted to register with the slots of an adjacent section and having means for holding the lands of one grate ring substantially in the center of the slots of an adjacent ring and means for holding said rings in concentric relationship. 20

4. A grate comprising a plurality of superimposed circular rings, the adjacent sides of which are provided with radial slots separated by narrower radial lands and means for holding said lands of one ring midway between the sides of said slots on the adjacent ring for the purpose 35 of forming two slots of approximately the width of the interposed land in place of a single slot extending between a pair of adjacent lands. 30
